CHEMICAL FIRE EXTINGUISHER HOLDER

James E. Rumfield, Henderson, Tex.

Application June 2, 1936, Serial No. 83,112

3 Claims. (Cl. 169—26)

This invention appertains to new and useful improvements in means for supporting chemical fire extinguishers, and especially of the bomb type.

5 The principal object of the present invention is to provide a holder for fire extinguisher bombs wherein the holder is constructed in such a manner as to automatically release the bombs at a predetermined high temperature.

10 Another important object of the invention is to provide a fire extinguisher bomb which is substantially automatic in operation to the extent of releasing the bomb to extinguish a fire.

15 Another important object of the invention is to provide a fire extinguisher bomb holder which is of simple construction and not susceptible to accidental release.

20 These and various other important objects and advantages of the invention will become apparent to the reader of the following specification.

In the drawing:

Figure 1 represents a side elevational view of the holder;

Figure 2 represents a top plan view of the holder;

Figure 3 is an end elevational view of the holder;

Figure 4 is a perspective of the wall plate.

Referring to the drawing, wherein like numerals designate like parts, it can be seen that the holder consists of the wall plate 5 having the struck-out portion 6, which is bent outwardly of the plate 5 and upwardly as shown in Figure 4 and provided with inwardly pressed rib portions 7. The wall plate 5 is provided with openings 8 through which screws 8a or other fastening means may be disposed for securing the plate 5 to a wall or other supporting structure. The plate 5 below the offset tongue 6 is provided with a horizontal slot 9.

40 The extinguisher holder further consists of the split band 10, preferably of metal, having the offset portion 11 at its intermediate part for disposition between the tongue 6 and the plate 5. Numeral 12 represents a disk curved horizontally and this has the end portions of the band 10 secured thereto as at 13. A pair of metallic members 14—15 are each provided with a hooked end 16, one of these hooked ends being disposed through the slot 9 in the wall plate 5, while the other hook 16 is disposed through a slot in the lower portion of the disk 12. The free ends of the strips 14—15 are soldered together as at 17 and

these members 14—15 serve to support a fire extinguishing bomb 18.

In the event of a sufficiently hot fire or heat application to the soldered portion 17, the soldered portion 17 will melt and permit the disconnection of the members 14—15 with the result that the bomb drops through the holder and breaks on the floor or some other structure so that the chemical can escape.

10 While the foregoing specification sets forth the invention in specific terms, it is to be understood that numerous changes in the shape, size, and materials may be resorted to without departing from the spirit and scope of the invention as hereinafter claimed.

15 Having described the invention, what is claimed as new is:

1. A fire extinguishing bomb holder comprising a wall plate, a struck out portion bent to define a hook on the wall plate, a bomb encircling band having a portion thereof disposed between the hook and plate for supporting the band in substantially horizontal position, and a thermostatically releasable support mounted beneath the band for supporting a bomb within the confines 20 of the band.

2. A fire extinguishing bomb holder comprising a wall plate, a struck out portion bent to define a hook on the wall plate, a bomb encircling band having a portion thereof disposed between the hook and plate for supporting the band in substantially horizontal position, and a thermostatically releasable support mounted beneath the band for supporting a bomb within the confines 25 of the band, said band having the portion between 30 the hook and the wall plate laterally offset to prevent circumferential movement of the band with respect to the plate.

3. A fire extinguishing bomb holder comprising a wall plate, a struck out portion bent to define 40 a hook on the wall plate, a bomb encircling band having a portion thereof disposed between the hook and plate for supporting the band in substantially horizontal position, and a thermostatically releasable support mounted beneath the 45 band for supporting a bomb within the confines of the band, said releasable support comprising a pair of strip members each swingably supported at one end, and a fusible substance interposed between the free ends of the strip members for 50 holding the same together in bomb supporting position.
